UNITED STATES PATENT OFFICE.

RALPH S. STRONG, OF CHICAGO, ILLINOIS.

CARBURETING DEVICE.

Application filed August 29, 1925. Serial No. 53,220.

My invention relates to improvements in connection with carbureting devices.

One of the objects of my invention is to provide a construction which will lessen crank case dilution.

A further object is to provide a construction which will facilitate starting a cold engine and which will lessen back-firing.

10 A further object of my invention is to provide a construction which will lessen the liability of flooding the carburetor.

A further object of my invention is to provide a construction which will economize fuel.

15 A further object is to provide a construction which will enable a car equipped with this device to get under way quickly.

Further objects will appear from the description and claims.

20 In a general way, I accomplish the objects of my invention by causing pulsations to occur in the mixture stream. This may be done in various ways, one being by the vibration of the throttle valve or a valve or shutter

25 in the mixture stream. I have found by test that all of the desired results indicated above are accomplished by this construction.

In the drawings, in which an embodiment of my invention is shown—

30 Figure 1 is a plan view of a gasoline engine and carburetor provided with my improved device;

Fig. 2 is a side elevation of the carburetor, parts being broken away to show the vibrating valve;

35 Fig. 3 is a plan view of the construction in Fig. 2;

Fig. 4 shows a detail of the connection from the throttle lever to the vibrating valve; and

40 Fig. 5 is a section on the line 5—5 of Fig. 3.

Referring to the drawings in detail, the construction shown comprises an internal combustion engine 1 which may be of any usual or suitable construction, provided with

45 a belt wheel 2 on the fan shaft 3, an intake manifold 4, and a carburetor 5 having a float chamber 6, an air inlet valve 7, a needle valve 8, and a throttle valve 9 which I also utilize as a vibrating valve for causing

50 pulsations to occur in the mixture stream. The carburetor construction may be of any suitable type and is not described in detail.

Between the vibratory throttle valve is inserted a construction known in the trade as a

55 Mayson valve 10, comprising a pair of clam shell valve members 11 which move in accord-

ance with the suction in the intake manifold, the valve opening being decreased as the suction increases. The Mayson valve per se forms no part of my invention, although it is 60 possible that it may be combined advantageously with my device for causing pulsations in the mixture stream.

In order to permit the slight vibration of the throttle required to give the desired pulsations, I provide a loose connection between the link 12 and the lever 13 secured to the shaft 14 of the butterfly throttle valve. This link forms part of the transmission from the usual throttle lever or accelerator to the 70 throttle valve. This lost motion connection shown in detail in Fig. 4 is provided by reducing the diameter of a portion of the stud or pin 15 which extends downwardly from the link 12, as shown at 16, so that this fits 75 loosely and has some play in the opening in the valve lever 13, thus permitting the required vibratory movement. If at any time it should be desired to eliminate the vibratory movement, this may be done by withdrawing the cotter pin 17 and lifting up the stud until the enlarged portion 18 of the stud fits in the opening 19, and as this fits snugly in the opening, there can be no vibratory movement. The pin may be held 80 in this raised position by re-inserting the cotter pin 17 above the valve lever 13. An opening 20 is provided at the lower end of the pin to receive another cotter pin to hold the pin 15 in place.

I have provided a construction having two selectively usable means for causing the valve to vibrate, one of which means gives a comparatively large amount of vibration and the other of which gives a lesser vibration. For 95 giving a comparatively large amount of vibration I mount an eccentric 21 on a pin 22 mounted on and extending upwardly from the valve lever 13, and cause this eccentric to rotate by means of a flexible shaft 23 driven 100 in any suitable manner, as from the belt pulley 2. This eccentric member 21 has a downwardly extending socket 24 into which the pin 22 on the valve lever extends loosely and this loose mounting together with the 105 eccentricity of the weight of the rotatable member 21, as shown in Fig. 3, causes a rapid vibratory movement of the valve lever 13 and causes corresponding pulsations to occur in the mixture stream.

110 I may find it desirable at times to disconnect this eccentric from the driving member

2 and for this purpose I mount the friction pulley 25 which engages the belt wheel 2 in such manner that it may be raised out of engagement with the belt wheel. For this purpose I mount the friction wheel 25 in a spring bearing 26 and extend an operating rod 27 back to the dash 28. The construction is such that if the rod 27 is drawn rearwardly it will cause the spring bracket 26 to swing upwardly and lift the friction wheel 25 out of driven engagement with the belt pulley 2. In order to hold the bracket in its raised position, I provide the end of the rod with a cross-pin 29 which cooperates with slots in a sleeve 30 secured to the dash. There are two pairs of these slots 31, each pair comprising two diametrically opposite slots, one pair being deeper than the other. When the rod 27 is turned so that the pin 29 is in the deeper pair of slots, the friction wheel 25 will be in driven engagement with the belt pulley 2, while when the pin is in the shallower pair of slots, the friction wheel will be out of engagement with the belt pulley.

However, I find that even with the friction wheel out of driven relation with respect to the belt pulley, there is still some slight vibratory movement of the valve 9 enough to cause slight pulsations to occur in the mixture stream. This may be due to the vibration of the car or engine affecting the valve lever 13, which carries the weight of the eccentric 21 and is yieldingly held by means of the spring 32. At any rate, I have found that such lessened vibrations do occur and that they cause vibrations in the mixture stream and affect the running of the engine favorably.

As indicated above, if for any reason it should be desired to entirely eliminate vibration of any sort, this can be done by connecting the pin to the valve lever in such a way as to eliminate any lost motion.

I have shown one method for causing vibrations, i. e., one form of valve and one means for vibrating said valve.

It is to be understood that I do not limit myself to the specific forms disclosed.

I claim:

1. In a carburetor construction, means for causing the formation and flow of a mixture of fuel and air, and means for causing periodic pulsations to occur in the mixture stream comprising a throttle member and mechanical means for causing periodic vibration of said throttle member independently of the action of the flow of the mixture.

2. In a carburetor construction, means for causing the formation and flow of a mixture of fuel and air, and means for causing periodic pulsations to occur in the mixture stream, said means comprising a throttle valve and mechanical means for causing periodic vibrations of said throttle valve independently of the action of the flow of the mixture, said last means comprising a rotatable driving member and transmission between said driving member and valve.

3. In a carburetor construction, means for causing the formation and flow of a mixture of fuel and air, and means for causing periodic pulsations to occur in the mixture stream, said means comprising a throttle valve, and mechanical means for causing periodic vibrations of said throttle valve independently of the action of the flow of the mixture, said last means comprising a rotatable eccentrically weighted member, said valve having a lever, on which said rotatable eccentric member is mounted.

4. In a carburetor construction, means for causing the formation and flow of a mixture of fuel and air, and means for causing pulsations to occur in the mixture stream, said means comprising a throttle valve and a plurality of selectively usable means for causing said valve to vibrate.

5. In a carburetor construction, means for causing the formation and flow of a mixture of fuel and air, and means for causing pulsations to occur in the mixture stream, said means comprising a throttle valve and a plurality of selectively usable means for causing said valve to vibrate, one of said means causing a greater vibration than the other.

6. In a carburetor construction, means for causing the formation and flow of a mixture of fuel and air, and selectively usable means for causing pulsations to occur in the mixture stream, said means comprising a throttle valve and means for causing said valve to vibrate.

7. In a carburetor construction, means for causing the formation and flow of a mixture of fuel and air, means for causing pulsation to occur in the mixture stream comprising a throttle member and mechanical means for causing periodic vibration of said throttle member independently of the action of the flow of the mixture, manually operable means for rendering said pulsation causing means operative or inoperative as desired.

In witness whereof, I have hereunto subscribed my name.

RALPH S. STRONG.
